UNITED STATES PATENT OFFICE

2,542,024

NOZZLE STRUCTURE FOR FLOOR AND SURFACE SWEEPERS

Edwin S. George, Bloomfield Hills, and Wesley A. Gibbons, Birmingham, Mich., assignors to Moto Mower Company, Detroit, Mich., a corporation of Michigan

Application October 24, 1944, Serial No. 560,160

2 Claims. (Cl. 15—354)

1

The present invention relates to improvements in cleaning and sweeping apparatus and, more particularly, to portable floor and surface sweepers.

The primary object of the invention is to provide a portable power-operated floor and surface sweeper with means for agitating or disturbing dust and dirt in corners, crevices, cracks and at the base of walls so that the dirt may be blown or directed into the path of the sweeper and picked up thereby.

Another object of the invention is to provide a portable power-operated floor and surface sweeper in which the rotary brush is driven by an internal combustion engine having its exhaust connected to a nozzle obliquely presented to the floor surface on one side of the portable sweeper so that the nozzle may be brought into play to direct a blast of exhaust gas at the base of walls and also into corners and crevices for the purpose of removing dirt and the like therefrom.

Another object of the invention is to provide a portable sweeper and cleaning apparatus of the above-mentioned type in which the nozzle for directing a blast of exhaust gas at the base of walls and into corners and crevices is adjustable so that it may be moved to any desired position to facilitate the quick and easy removal of dirt and dust without employing extraneous brushes and brooms as well as other cleaning devices.

Another object of the invention is to provide a portable cleaning and sweeping apparatus of the above-mentioned character which will need little attention and will operate efficiently from the exhaust gases of the power motor, thereby eliminating the use of air fans or blowers or the like.

Other objects and advantages of the invention will become apparent during the course of the following description of the accompanying drawings, wherein:

Figure 1 is a side elevational view of the floor and surface cleaner, illustrating an embodiment of the invention showing the manner in which the adjustable nozzle is supported from the machine;

Figure 2 is a top elevational view of the floor and surface cleaner further illustrating the location of the adjustable nozzle and the manner in which the same is positioned to direct a blast of exhaust gas over the floor or surface; and

Figure 3 is a vertical cross-sectional view taken on line 3—3 of Figure 2, looking in the direction of the arrows showing the manner in which the nozzle is adjustably supported and pivotally attached to the sweeper frame.

2

In the drawings, there is shown a portable floor or surface sweeper, including a wheeled frame 5 of U-shaped form providing front and side frame members 6 and 7 respectively. The 5 ends of the frame members 7 are connected by a transverse bar 8 held in place by suitable U-bolts as at 9. Affixed to the transverse bar 8 is a motor platform 10 having a pair of axle housings 11 for supporting a rear axle 12. Rubber-tired 10 supporting wheels 13 are mounted on the axle 12 for supporting the rear end of the wheeled frame 5 while the front end is supported by a swivel caster 14, mounted in a suitable swivel bracket carried by the front frame bar 6. Spaced 15 from the front frame bar 6 there is a transverse swinging bar 15 and the swivel bracket 16 is secured to the front bar 6 and transverse bar 15. The front end of the motor platform 10 is supported on a transverse frame bar 18 riveted or 20 otherwise secured to the side frame bar 7.

A traction motor 19, such as an internal combustion engine or the like, is suitably supported upon the motor platform 10 and has its power take-off shaft 20 provided with a sprocket wheel 21 which is drivingly connected to a power shaft 22 having its ends journaled in suitable bearings 23 carried by the side frame members 7. A sprocket chain 24 is trained over the sprocket wheel 21 and over a sprocket wheel 25 carried by the power shaft 22 to impart rotation thereto. The internal combustion engine 19 includes the usual cylinder casting 26 having an engine head 27 which is provided with the usual valve gearing, and an exhaust manifold 28 is connected with the engine 27 for accommodating the escape of exhaust gases. Also mounted on the power shaft 22 is a sprocket wheel 29 which is drivingly connected with an axle 12 by means of a sprocket chain or the like as at 30 which is trained over a sprocket 35 wheel 31 keyed to the axle 12.

Secured to the side frame members 7 is a pair of casing plates 32 which are bolted or otherwise fixed in position as at 33. A rotary brush is adapted to be supported between the casing members 32 and a rotary shaft 34 has its ends journaled in said end casing members 32 for free rotation therein. The rotary brush 35 is of cylindrical form and is supported in such a manner as to engage the surface or floor and sweep the same when the rotary brush 35 is rotated by a motor 19. In order to rotate the brush 35, a drive sprocket chain 36 is trained over a pulley or sprocket wheel 37 secured to one end of the shaft 22, and said drive chain is trained over a pair of idle sprockets 38 and 39 (Figure 1) so as to be

looped about a sprocket wheel 40 carried by one end of the rotary shaft 34.

An arcuately curved cover 41 extends between the end casing section 32 and terminates in a forwardly directed lip 43 for supporting the forward edge of a removable dust-collection receptacle 44 in any suitable manner, so that the brush 35 when rotated in a clockwise direction will sweep dust and other foreign matter upwardly over a transverse plate 45 and over the lower flanged edge 46 of the dust-collection receptacle 44.

Pivoted to the motor platform 10 is a handle shaft 48 having a handle 49 for guiding the sweeper over the floor surface and said handle 49 is provided with suitable conventional control members (not shown, and forming no part of the present invention) for regulating the speed of the internal combustion engine 19.

Also driven by the power shaft 22 is a rotary pump 50 by means of a sprocket chain 51 and said rotary pump is supported on a platform 53 extending rearwardly from the transverse frame bar 54. A pair of frame brackets 56 are secured to the side frame members 1 and are connected in the front by a transverse frame bar 57 and the transverse frame bar 54 above mentioned. A liquid supply tank 58 is supported on the transverse frame bars 54 and 57 and said tank is provided with an outlet pipe 59 which is connected to the inlet of the pump 50 as illustrated in Figure 1. The outlet of the pump is connected to a discharge pipe 60 having a spray manifold 61 extending transversely of the wheeled frame 5 and supported by suitable brackets or the like as at 62. Spray nozzles 63 extend downwardly from the spray manifold 61 and are arranged with their orifices in spaced relation from the surface of the ground over which the sweeper is being propelled. A control valve 64 is interposed between the discharge pipe 60 and manifold 61 and said valve is provided with a lever 65 which is adapted to be controlled from a location adjacent the handle 49 by means of a control handle 66 through the medium of suitable flexible shafting as at 67.

Secured to the exhaust manifold 28 is a muffler 68 having a pipe fitting 69 at one end thereof which is elbowed and extends upwardly so that the upper end may be connected to a filter element 70 by a suitable gland nut or the like as at 71. The upper end of the filter 70 is provided with a removable closure 72 having a gland nut or the like as at 73 to which is attached a flexible hose 74. The flexible hose is supported from the gas filter 70 by a bracket 75 and has its lower end further supported by means of a bracket 76 secured to one of the side frame members 7 by bolts or the like as at 77. The lower end of the flexible hose 74 is connected to a nozzle 78 having a laterally extending projection 79 which is pivoted to one of the side frame members 7 by means of a bolt as at 80. A coil spring 81 is interposed between the head of the bolt 80 and the side frame member 7 to frictionally tension the lateral extension 79 and yieldingly hold the nozzle 78 in an adjusted position. Formed integral with the extension 79 is a handle lever 82 for the purpose of rocking the nozzle 78 on its pivot 80 to various positions of adjustment. The free end of the nozzle 78 is bent laterally and forwardly as at 84 and terminates in a flattened flared end portion 85 to provide an elongated orifice 86 which is so positioned and arranged as to be presented obliquely to the floor or surface over which the portable sweeper and cleaning apparatus is being pro-

pelled. Preferably, the nozzle 78 is located and positioned on the right hand side of the wheeled frame 5 adjacent the forward end thereof so that by manipulating the portable sweeper, the end of the nozzle 78 may be directed into corners and crevices of a building or the like so as to remove dirt therefrom and blast the same into the path of the rotary brush 35. By simply adjusting the hand lever 82, the nozzle 78 may be adjusted to produce the most beneficial effect so that the blast of exhaust gases will be directed into corners and crevices as above described.

In operation, the internal combustion engine 28 is started in the usual manner to cause the rotary brush 35 to be rotated so as to pick up and sweep dirt into the dirt and dust collection receptacle 44. Simultaneously, the internal combustion engine 19 propels the sweeper over the floor or surface at a speed which may be governed or regulated by the hand control adjacent the handle 49 as above described so that the machine may be propelled forwardly at the proper speed. The tank 58 may be filled with a suitable dust-laying liquid for being sprayed in advance of the rotary brush 35 under pressure, to thereby eliminate as much as possible the contamination of the air with dust particles and dirt.

When the sweeper is employed adjacent corners, joints or crevices, the exhaust gases from the internal combustion engine 28 will pass through the exhaust muffler 68, gas filter 70, flexible tubing 74 and through the nozzle 78 so as to direct the blast of exhaust gases into the corner for the purpose of removing dirt and foreign matter therefrom and spreading the same over the floor surface so that it may be eventually picked up by the rotary brush 35.

It is to be understood that the form of the invention herewith shown and described is to be taken as a preferred embodiment of the same and that various changes may be made in the shape, size and arrangement of parts without departing from the spirit of the invention or the scope of the subjoined claims.

What we claim is:

1. The combination in an engine-driven rotary floor brushing machine of a wheel-supported frame structure, a rotary brush rotatably mounted on said frame structure, an internal combustion engine mounted on said frame structure and drivingly connected to said brush, a gas blow nozzle mounted on said frame structure forwardly and to one side of said brush, said nozzle having a laterally elongated outlet directed forwardly, downwardly and outwardly relatively to said frame structure adjacent the floor with its long axis directed obliquely to the floor, and an exhaust gas conduit extending from the exhaust connection of said engine to said nozzle.

2. The combination in an engine-driven rotary floor brushing machine of a wheel-supported frame structure, a rotary brush rotatably mounted on said frame structure, an internal combustion engine mounted on said frame structure and drivingly connected to said brush, a gas blow nozzle mounted on said frame structure forwardly and to one side of said brush and having a portion thereof pivotally engaging said frame structure on an approximately horizontal pivot axis, a resilient member engaging and urging said nozzle portion into yielding frictional engagement with said frame structure, said nozzle having a laterally-elongated outlet directed forwardly, downwardly and outwardly relatively to said frame structure adjacent the floor with its long

axis directed obliquely to the floor, and an exhaust gas conduit extending from the exhaust connection of said engine to said nozzle.
